UNITED STATES PATENT OFFICE.

CARL O. WILLIAMS, OF AKRON, OHIO.

FILING CABINET.

Application filed May 25, 1923. Serial No. 641,427.

To all whom it may concern:

Be it known that I, CARL O. WILLIAMS, a citizen of the United States, residing at Akron, in the county of Summit and State 5 of Ohio, have invented new and useful Improvements in Filing Cabinets (Case B), of which the following is a specification.

This invention relates to improvements in filing cabinets especially adapted for use in 10 connection with keeping a record of stock, an object being to provide a cabinet wherein record or like cards may be arranged for convenient reference.

Another object of the invention is the 15 provision of a cabinet of this character which may be divided into separate sections, each of which may contain any desired number of compartments for individual records, novel means being provided for separating 20 the cabinet into these sections, whereby the number of compartments may be increased or reduced at will and for indicating the general and particular character of the sections and compartments.

25 Another object is the provision of a division member adapted to display legends to advantage and also adapted to be fitted in file compartments of various widths and this without materially detracting from the 30 capacity of a compartment member, and the portions of the said end wall being adapted to bear legends.

With the above and other objects in view, the invention further includes the following 35 novel features and details of construction, to be hereinafter more fully described, illustrated in the accompanying drawings and pointed out in the appended claims.

In the drawings:—

40 Figure 1 is a front elevation of a cabinet constructed in accordance with the present invention.

Figure 2 is an enlarged elevation of a portion 45 of the cabinet showing in detail the arrangement of the compartments and the manner of dividing the cabinet into sections.

Figure 3 is a sectional view on the line 3-3 of Figure 2.

50 Figure 4 is a plan view of a blank from which one of the division members is formed.

Figure 5 is a perspective view of one of the division members ready for use.

Referring in detail to the drawings where- 55 in like characters of reference denote corresponding parts, the cabinet which is indi-

cated generally at 10 may be of any suitable character and may be supported upon a table 11. If desired, this table may contain a case 12 within which is arranged suitable 60 record cards 13 for use within the cabinet.

The cabinet 10 is formed with a number of individual compartments 14 which are arranged in tiers and are separated by means of horizontally arranged partitions 15 so as 65 to provide a plurality of pigeon holes.

The invention resides in the means whereby the cabinet may be divided into a number of separate sections, each of which will contain a group of compartments 14, the 70 number of which may vary as desired. For this purpose there is provided a division member 16 which is formed of a single sheet of material shown in Figure 4. The sheet is bent or folded along the dotted lines 75 16' so as to provide spaced substantially parallel side walls 17 which are connected at one end by a substantially V-shaped end wall 18. A substantially U-shaped division member 16 is thus provided which is of a 80 width to be received within any of the compartments 14 and to frictionally engage the side walls of the said compartments with the V-shaped end wall preferably extending beyond the walls of the compartments 85 14.

As an example of the use of the invention, particularly reference may be had to Figure 2 of the drawings wherein the division members 16 are shown as dividing a portion 90 of the cabinet 10 into separate sections. One of these sections is illustrated as used for keeping a record of apples, another section for beans, another for soap and a fourth for tea. The general character of each section is shown by indicia upon the V-shaped end walls 18, the section A being devoted to apples, the section B to beans while the sections C and D are devoted respectively to 95 soap and tea. As previously stated, these sections may contain any number of individual compartments 14, depending upon the purpose for which the section is utilized and each individual compartment may be provided with indicia indicating the particular character of the compartment. For example, the apple section A has its separate compartments labeled with the names of different kinds of apples while the individual compartments of the section B contain indicia indicating various kinds of beans. The sections A and B each contain 100 110

four compartments, but this number may be increased or decreased by moving or rearranging the division numbers in different compartments, it being noted that the section C contains six compartments for various kinds of soap.

It will be thus apparent that the invention provides an exceedingly simple and efficient means whereby a cabinet of this character 10 may be divided into separate sections containing any number of individual compartments and it may thus be adapted not only for the purpose described, but may be utilized for various other purposes.

15 As clearly shown in Figure 3, the space between the side walls 17 of the division member 16 may be utilized to receive files, cards or the like.

The projecting V-shaped portion of each 20 division member 16 also permits of the division member being readily withdrawn; and it will be also noted that each of the division members may be increased or diminished in width as the occasion demands.

25 The invention is susceptible of various changes in its form, proportions and minor

details of construction and the right is herein reserved to make such changes as properly fall within the scope of the appended claims.

30

Having described the invention what is claimed is:

1. As a new article of manufacture, a division member for use in a compartment of a case comprising a plurality of compartments the said division member having spaced side walls and a V-shaped end wall joining the side walls at one end of the member, and the portions of the said end wall being adapted to bear legends.

35

2. The combination with a case comprising a plurality of compartments of division members disposed in certain of the compartments and spaced apart, each of the said division members having spaced side walls 45 and also having a V-shaped end wall joining the outer ends of the side wall and projecting beyond the face of the case, the portions of the said end wall being adapted to bear legends.

40

In testimony whereof I affix my signature.

CARL O. WILLIAMS.
